AMUSEMENT APPARATUS

Louis De Marco, Cleveland, Ohio

Application February 24, 1936, Serial No. 65,235

6 Claims. (CL 273—102.2)

This invention relates to an amusement apparatus.

One object of the invention is to construct an improved apparatus of this character wherein amusement is created by testing one's skill in shooting at a target.

Another object of the invention is to construct an apparatus of this type having an improved target mechanism providing means whereby each hit on any portion of the target is indicated by a signal and such hit is recorded by the gravitation of the impelled missile into a valued pocket or collector.

Another object of the invention is to provide an apparatus of this type which is relatively simple and economical in construction, comprises few operating parts and operable in a ready manner.

Other objects of the invention will be apparent to those skilled in the art to which my invention relates from the following description taken in connection with the accompanying drawings, wherein—

Fig. 1 is a plan view of an apparatus embodying my invention.

Fig. 2 is a side view showing the missile impelling mechanism and a contestant holding the latter ready to make a shot.

Fig. 3 is a section on the line 3—3 of Fig. 1.

Fig. 4 is a section on the line 4—4 of Fig. 3.

Fig. 5 is a section on the line 5—5 of Fig. 2.

Fig. 6 is a fragmentary section on the line 6—6 of Fig. 5.

Fig. 7 is a fragmentary elevation of one of the target members, parts being broken away.

Fig. 8 is a section on the line 8—8 of Fig. 7.

Fig. 9 is a fragmentary section showing a target member in operated position.

Fig. 10 is a fragmentary section, similar to parts shown in Fig. 3 slightly enlarged.

Fig. 11 is a view on the line 11—11 of Fig. 10.

Fig. 12 is a diagrammatic view.

In the drawings, 1 indicates as an entirety a casing constructed to provide a target mechanism 2 toward and into which suitable missiles, preferably balls 3, are impelled by an impelling mechanism 4. The casing 1 may be mounted on any desired supporting means, for example, front and rear legs 1x, 1x', the latter being adjustable for a purpose later set forth. The impelling mechanism 4 preferably consists of a gun having a stock 4a adapted to be placed against the contestant's shoulder and a barrel 4b which gives direction to each ball when impelled. The impelling means embodied in the gun is shown as consisting of a bow 4c, the cord of which is adapted to engage

a trigger. The bow cord extends through aligned slots in the lateral walls of the barrel 4b and slides therein when being engaged with the trigger or when acting to impel a ball 3. With the bow in set position, as shown in Fig. 2 and with a ball 3 in position, operation of the trigger will release the cord and permit the latter to impel the ball substantially on the line indicated by the arrows a (Fig. 2).

The gun may be constructed in any desired manner; that is, the impelling force may be provided by a spring operated plunger or by means of such a plunger adapted to compress air in the barrel to force the ball toward the target mechanism. Where the gun is of the bow type, as shown, either the bow or the cord may be formed of resilient material; for example, the bow arms may be connected by a coiled spring.

The target mechanism consists of a bull's-eye 5 and concentric openings 6 formed in transverse walls 7 which are disposed in spaced relation forward of the bull's-eye, said walls 7 and side walls 1a of the casing 1 forming receiving compartments 8 into which the balls fall, as later set forth, whereby the skill and accuracy of the contestant using the impelling mechanism 4 may be determined. By preference, the rearmost transverse wall 7 is provided with the bull's-eye 5 centrally of the opening 6 therein. All of the openings 6 forward of the bull's-eye may be of successively larger diameter, but in the preferred arrangement the outer openings 6 are of different diameter and the inner openings 6 have a diameter equal to that of the openings 6 around the bull's-eye 5. Due to the fact that the impelled ball traverses a trajectory curve, this arrangement of the openings 6 affects the ease of making a bull's-eye hit and hence calls upon the contestant to exert greater skill in hitting the bull's-eye 5 or shooting the ball 3 into one of the rearmost compartments to secure a higher score.

The bull's-eye 5 consists of a convexed member mounted on an arm 5a which is pivotally mounted on the rear side of the rearmost transverse wall 7. The bull's-eye is of convexed shape so that if hit by a ball, the latter will be deflected rearwardly into the compartment 8 rearward of the bull's-eye and thus be guided into the highest valued pocket, as later set forth. A spring 5b normally acts on the arm 5a to maintain the bull's-eye in position. The bull's-eye is provided with a striker 5c which is arranged to strike a gong 9 mounted on the rear wall 1c of the casing 1.

The marginal edge of each wall 7 and 1b sur-

rounding the opening 6, on its outward face or side is provided with a circumferential member 10 similar in shape to the opening and serving as a guard for such edge to protect it against the impact of the missiles and also as a deflector for the latter. That is, the ball 3 may hit the guard member 10 and be arrested in its projected path and thus drop into the compartment 8 in front of the member or it may be deflected by the member 10 into some other pocket. For this latter purpose the inner edge of the member 10 is curved inwardly and rearwardly which, to form a deflecting surface, when hit by a missile, deflects it at an angle rearwardly into a rearward compartment, whereby the contestant wins a higher score.

By preference, each member 10 is loosely mounted on guides carried by the front face of the adjacent partition wall 7 so that the portion 20 hit by a missile or the entire member may be moved toward the wall to effect the operation of a signalling device, such as a bell. The guides for each member 10 may consist of screws 11, the heads of which limit the outward movement of 25 the member. The screws 11 are uniformly positioned around the adjacent opening 6. Between the screws 11 I provide coiled springs 12 which normally tend to maintain the member 10 spaced from the adjacent wall 7 and in engagement with the screw heads. The signaling means actuated by each member 10 preferably consists of an electric bell 13, the circuit for which is closed by the movement of each member 10 against the tension of the spring or springs 12 when hit by a missile. For this purpose, the member 10 is formed of suitable conducting material and when any portion of it engages a contact 14 fixed to the adjacent wall 7, a circuit 15 connected to the terminals of the bell 13, is closed 40 to ring the latter. Each contact 14 preferably consists of a ring of suitable conducting material countersunk in the adjacent wall 7 and connected to a terminal 16 for a lead 15a. Each member 10 is provided with a terminal for a lead 45 15b. As will be apparent from Fig. 12, each pair of leads 15a, 15b, is connected to the electric mains, so that the movement of any member 10 will effect the closing of the circuit for the signaling device 13 to indicate a hit. As the device 50 9 is capable of producing a sound different from the bell 13, the contestant can tell when the bull's-eye or one of the target members 10 has been hit.

17 indicates a trough located in each compartment and arranged to collect the missiles falling thereinto and discharge them into guide means indicated as an entirety at 18. Each trough 17 is substantially U-shape in cross section and of a width to engage the opposed faces of the transverse walls 7 forming the adjacent compartment. Each trough is of curvilinear shape longitudinally so as to extend around the adjacent opening 6 and upwardly at either side thereof the ends of the trough engaging the side walls 1a. The bottom portion of each trough 17 is formed with an opening through which the missiles gravitate into the adjacent guide or runway 18, preferably a tube. The tubes 18 extend in an inclined direction and pass through the front wall 1b, and forward of the casing 1, in line therewith, along an extension 20, their outer ends terminating in pockets or collectors 21, into which the missiles gravitate and come to rest. The pockets 21 are given desired values, such as 10, 20, 30, etc., so 75 that a score of the hits may be computed; for

example, if the missile lands in the first compartment 8, the missile will roll through the tube 18 to the pocket valued 10, each succeeding compartment having a higher scoring value; the highest score being for the missile shot past the bull's-eye 5 into the last compartment 8, which corresponds to the pocket valued 100. The extension 20 leads to a point in front of the shooting position (see Fig. 2) so that the contestant may readily reload the gun. The extension 20 consists of an inclined chute extending forwardly of and in line with the casing 1, the outer end of the chute being closed to form a receiving chamber 22. The extension 20 at its outer end inwardly of the chamber 22 is provided with a 15 cross member 23 on which the collectors 21 are mounted. The guide tubes 18 extend longitudinally of the chute 20 and extend through the member 23 so as to discharge the missiles into the pockets 21. The pockets are connected together as a unit and consist of a curved bottom wall 24 having division walls 25. The inner edge of the wall 24 is rolled around a rod 26 the ends of which are rotatably mounted in brackets 27 fixed to the wall 23. One end of the rod 26 is 23 provided with a handle 28 which is adapted to swing the pockets away from the wall 23 (see dotted lines in Fig. 6) to discharge the balls into the chamber 22. A spring 29 serves to maintain the pockets in position against the wall 23. The 30 bottom wall of the chamber 22 is inclined toward one side (see Fig. 5) so that the balls will gravitate to one point. By providing a chute, as shown at 20 and arranging it in line with the casing 1, any balls, when shot, fall short of the forward-most compartment 8, and they will drop into the chute and roll through the opening 23a into the chamber 22.

I provide a suitable light 29 for the bull's-eye. The light is preferably arranged on the outer 40 side of the rear wall 1c in operative relation to an opening 30 formed therein and on the inner side of the wall 1c, over the opening 30, I provide a plate 31 formed with a multiplicity of openings through which the light rays project. The opening 30 is of the same diameter as the opening 6 in which the bull's-eye is mounted and permits the contestant to see the bull's-eye as the latter is directly interposed in the line of vision.

To permit access to the interior of the casing, 50 one side wall is hinged along its upper edge, as illustrated in Fig. 4, but may be locked in closed position by a lock 32.

The target mechanism is shown disposed in a horizontal position; that is, the axis common to the openings 6 extends horizontally substantially in line with the eyes of the average contestant, but where the latter is tall or short in stature, the target mechanism may be adjusted to dispose the axis of the openings according to the height 60 of the contestant. For this purpose, the rear leg 1z' is adjustable in length and when adjusted the axis of the openings will be inclined to bring it into coincidence with the line of vision between the contestant's eyes and the bull's-eye. In the illustrated construction for making this adjustment, Figure 4, I make the rear leg in sections and provide on each a bracket 32 having a threaded boss 33, one boss having a right-hand thread 70 and the other boss having a left-hand thread. The bosses 33 are connected by a screw 34 having threaded portions at its ends which extend through the bosses, so that by turning the screw by means of the hand-wheel 35 attached thereto, 75

the rear end of the casing 1 is raised or lowered to effect the required adjustment.

To those skilled in the art to which my invention relates, many changes in construction and widely differing embodiments and applications of the invention will suggest themselves without departing from the spirit and scope of the invention. My disclosures and the description herein are purely illustrative and are not intended to be 10 in any sense limiting.

What I claim is:

1. In an amusement apparatus, a target comprising a casing having a plurality of transverse partitions spaced apart throughout the length 15 of the casing and having central openings therethrough of different diameters, a bull's-eye mounted on the innermost partition within the opening thereof, a ring mounted on the forward side of each of said partitions to move substantially axially of the opening therein, the inner marginal portion of each of said rings being shaped in cross section to form a deflecting wall and having a diameter less than that of the adjacent opening, springs normally tending to move 20 each said ring away from the adjacent partition, a signal device connected to said deflector rings for actuation upon the movement thereof under impact of a projectile, troughs disposed between the lower portions of said partitions for collecting 25 projectiles deflected into the spaces provided between the partitions, and independent collecting devices leading from said troughs for carrying off projectiles settling in the troughs.

2. In an amusement apparatus, a target comprising a casing having spaced transverse partitions therein providing a series of independent compartments, said partitions having substantially aligned openings therethrough of different diameters and each provided on its forward side 30 with an annular contact in concentric relation to the adjacent opening, a bull's-eye mounted on the innermost partition in the opening thereof, a ring mounted on the forward side of each of said partitions to move substantially axially of the opening therein, the inner marginal portion 35 of each of said rings being shaped in cross section to form a deflecting wall and having a diameter less than that of the adjacent opening, springs normally tending to move each said ring away from the adjacent partition, electric circuits connected to said contacts and rings and including a signaling device, the outer marginal edge of each said ring being arranged to engage the adjacent contact to close a circuit when the ring is depressed by impact, independent tubes leading from the bottoms of said compartments for receiving projectiles settling therein, and independent receptacles at the outer ends of the tubes for receiving the projectiles from the tubes 40 and adapted to be contradistinguished from one another for determining the particular compartments from which the projectiles are collected.

3. In an amusement apparatus, a target comprising a casing open at its forward end and provided with a plurality of spaced apart transverse partitions having aligned openings of different sizes therethrough and each provided on its forward side with an annular contact, a bull's-eye mounted in the inner end of the casing in line with said openings, deflector rings disposed concentrically to said openings at the forward sides of the partitions and the front of the casing, resilient supporting means for said deflector rings to admit movement thereof under impact of pro-

jectiles for cushioning the impact and for moving the rings, electric circuits connected to said contacts and rings for a signaling means arranged upon the movement of each of the rings to close a circuit to operate the signal means, collecting troughs disposed between the lower portions of the partitions to collect projectiles deflected therein by said rings, an independent tube leading from each trough to carry off the projectiles therefrom, an independent receptacle disposed at the outer end of each tube for receiving the projectiles therefrom, means for contradistinguishing said receptacles to designate the receptacles relatively to the respective trough between the partitions, means for dumping said receptacles, and collecting means disposed beneath the receptacles for receiving the projectiles therefrom when the receptacles are dumped and for maintaining the projectiles in position for subsequent use.

4. In a game apparatus, the combination of a casing provided interiorly with a bull's-eye and a plurality of spaced partitions forward thereof, said partitions being formed with aligned openings increasing in diameter forwardly from said bull's-eye, an annular contact mounted on the forward side of each said partition concentric to the opening therein, a signaling device, a ring concentrically related to each opening on the forward side of the adjacent partition, cushioning means for yieldably supporting each of said rings on the forward sides of said partitions and normally tending to move the ring away therefrom, electric circuits between said signal device and each said contact and the adjacent ring, the inner marginal portion of each said ring being shaped to form a wall for deflecting projectiles into one of the spaces between said partitions and the outer edge of each said ring being arranged to engage the adjacent annular contact due to impact of a projectile on said ring to close one of said circuits, and means for discharging the projectiles from the spaces between said partitions.

5. An apparatus as claimed in claim 4 wherein means are provided for adjusting vertically one end of said casing to dispose the axis of said openings at an inclination to the horizontal.

6. In an amusement apparatus, a target comprising a horizontally disposed casing having between its front and rear ends spaced transverse partitions providing a series of independent compartments and formed above the bottoms thereof with aligned openings of different diameters, the larger opening being at the front and each rearward opening being smaller than the adjacent forward opening, a bull's-eye mounted on the innermost partition in the opening therein, a ring mounted on the front side of each partition forward of said bull's-eye and in concentric relation to the opening therein and arranged to yield due to impact of a projectile, the inner marginal portion of each of said rings being shaped in cross section to form a curvilinear deflecting wall and having a diameter less than that of the adjacent opening, independent tubes leading from the bottoms of said compartments for receiving projectiles settling therein, and independent receptacles at the outer ends of the tubes for receiving the projectiles from the tubes and adapted to be contradistinguished from one another for determining the particular compartments from which the projectiles are collected.

LOUIS DE MARCO.
